CLAIM

The ornamental design for a combined display kiosk and dispensing stand, as shown and described.

DESCRIPTION

FIG. 1 is a perspective view of a combined display kiosk and dispensing stand showing my new design;

FIG. 2 is a front elevational view, the rear being a mirror image thereof;

FIG. 3 is a right side elevational view, the left side being a mirror image thereof; and,

FIG. 4 is a top plan view thereof.
